WIRE FORMING FIXTURE

Gerard A. Frank, Allentown, Pa., assignor to Western Electric Company, Incorporated, New York, N. Y., a corporation of New York

Application October 14, 1954, Serial No. 462,302

7 Claims. (Cl. 140—71)

This invention relates to a wire forming device and particularly to a fixture for progressively bending wires or strip material to a desired configuration.

With the current development of transistors, varistors and other point contact semi-conductor devices, there arose a definite need for a device for making accurate and uniform S bend wire contact members therefor. Some devices currently used for bending such contact members utilize a single forming operation of single or double acting forming dies. With this type of operation, however, undesirable internal stresses are set up in the wire and the wire is stretched non-uniformly.

It is, therefore, the principal object of this invention to eliminate the troubles encountered by such devices, making it possible to produce uniform, complex bends in wires without objectionably stretching them.

A specific embodiment of the invention has a plurality of spring biased, opposed, movable forming members between which the wire to be formed is positioned. The forming members are controlled by a driven actuator having camming means for each of the members. By driving the actuator, the forming members are successively released, and due to the spring bias thereon, move to progressively bend the wire located therebetween. In this progressive bending operation the slack required for the bends is pulled in from the free end of the wire thereby preventing stretching of the wire.

According to a feature of the invention, the camming means for each of the forming members is individually adjustable making it possible to vary the actuating sequence or the relative timing of the actuation of the individual forming members. This arrangement is useful for special type bends where deformation, stretching or weakening of a certain portion of the bend is required.

These and other features of the invention will be more readily understood from the following detailed description taken in conjunction with the accompanying drawing, in which:

Fig. 1 is a partially broken, isometric view of a forming fixture according to the invention;

Fig. 2 is a partially broken, side elevational view of part of the fixture shown in Fig. 1;

Fig. 3 is a cross-sectional, side elevational view of a portion of the fixture showing the forming members fully actuated;

Fig. 4 is an isometric view of the cams on the actuator of the fixture showing the actuator in phantom; and

Figs. 5, 6 and 7 are side elevational views of a portion of the forming members of the fixture showing steps in the progressive bending of a wire.

Referring now to the drawing, particularly Fig. 1, in general the fixture consists of a base member 36, having a vertical support member 16 on which opposed forming members 9, 10, 11 and 12 are slidably mounted, an actuator 30 for the forming members, a driver 35 therefor, and ways 15 (only one shown) for guiding and supporting a wire holder 14 (shown in phantom) so that the wire

2

8 extending therefrom will be positioned between the opposed forming members. The wire holder may consist of a simple clamp for the wire extending therefrom or it may be of the type for holding two wires as disclosed in 5 Patent 2,688,267 to K. A. Schmuldt, dated September 7, 1954.

Y-shaped slide members 17, 18, 25 and 26, to which the forming members 9, 11, 10 and 12 respectively are secured, are mounted for vertical, reciprocating movement 10 on the member 16. The upper slides 17 and 18 are provided with guides 19, 20 and 21 for restricting the slides for such movement and the lower slides 25 and 26 are restricted to similar movement by guides 19, 40 and 21 the outside guides 19 and 21 being used for both upper 15 and lower members and the middle guides 20 and 40 being of similar cross-sectional dimensions but must be separated from each other to provide the opening for insertion of the wire between the forming members.

As seen in Fig. 1, one side 46 of upper member 9 is of 20 reduced thickness and overlaps a similarly reduced thickness side 47 of member 11, the lower ends of these portions 46 and 47 being provided with bending surfaces 48 and 49 respectively shaped for the particular bend desired. In like manner the lower members 10 and 12 are provided with reduced thickness overlapping sides 52 and 53 25 with bending surfaces 50 and 51 (Fig. 3) respectively at the upper ends thereof.

Springs 22 and 23, on bolts 55 and 56 which are 30 screwed into slide members 17 and 18 respectively are compressed between the ends of the slide members and a fixed end member 24 on the top of support 16, the bolts 55 and 56 making sliding fits through holes 61 and 62 respectively. The springs apply a downward driving force to the members 9 and 11 respectively. In a similar 35 manner springs 27 and 28 on bolts 57 and 58, compressed between the ends of guide members 25 and 26 respectively and the fixed end member 29 on the bottom of support 16 apply an upward driving force to the members 10 and 12 respectively. The vertical travel of the forming members may be adjusted by changing the position of nuts 34 on their bolts 55, 56, 57 or 58 or by screwing the bolts into or out of their respective slide members. These bolts, or nuts 34 thereon, must be pre-set for the particular bend to be made in the wire. The spring tensioning on the guide members may be varied by moving the nuts 33 on the bolts.

The forming members 9, 10, 11 and 12 are held apart, to permit the insertion of the wire 8 therebetween, by an actuator member 30 which is supported for reciprocating motion in housing 31 mounted on base member 36. The actuator normally occupies a forward position whereby individual actuating cams 41 and 43, reacting on the bottom surfaces of slides 17 and 18 respectively, and cams 42 and 44, reacting on the top surfaces of slides 25 and 26 respectively, hold the members 9 and 10, and 11 and 12 apart. As mentioned above, the cams are slotted so that they may be individually positioned on the actuator member 30 for changing the sequence of actuation of the forming members if the forming of a particular bend may be required. As seen in Fig. 4, for the progressively formed S bend described herein, the cams 41 through 44 are staggered on the actuator member 30 to permit a similar staggered actuation of the forming members 9 through 12 as the member 30 is retracted. Thus cam 42 for the slide 25 of forming member 10 occupies the furthest removed position and cam 43 for the slide 18 of forming member 11 occupies the furthest forward position with respect to the holder 14, cams 41 and 44 for slides 17 and 26 of forming members 9 and 12 respectively occupying intermediate positions on the actuator 30.

An air cylinder actuator or driver 35 connected to the

actuator member 30 is mounted on the base 36 and is provided for retracting the cams from the forming members allowing them to converge successively on one another since their relative positioning on member 30 permits member 10 to reach its ultimate position first; member 9, second; member 12, third, and member 11 last to form the wire 8 as seen in Fig. 3. The wire 8 is completely formed by the contoured surfaces 50, 48, 51 and 49 when the actuator 30 is moved to its fully retracted or withdrawn position. The S bend, as progressively formed, is shown in Figs. 5, 6, 7 and 3. Fig. 5 shows member 10 moved to its actuated position with the end surface 50 resting upon the wire 8. Fig. 6 shows the member 9 being lowered the surface 48 thereof producing the first bend in the wire 8. Fig. 7 shows member 12 moved, the surface 51 thereof producing the second bend in the wire and Fig. 3 shows the final step where member 11 is lowered and the surface 49 thereof completing the bend. In the sequential operation of these members, controlled by the staggered positioning of the cams 41, 42, 43 and 44 on the actuator member, the cams sliding on the beveled surfaces of guides 25, 17, 26 and 18 permit the spring tension, caused by springs 27, 22, 28 and 23, to successively advance the members 10, 9, 12 and 11, respectively, to form the wire.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. In a device for forming complex bends in wires, a plurality of spring biased, opposed, movable forming members, said opposed members having surfaces adapted to co-act to form a portion of the bend, an actuator normally holding the members apart, means for moving the actuator and individual cams for each of the members on the actuator for releasing the forming members to converge on a wire positioned between the members when the actuator is moved, the releasing, and therefore the wire forming sequence being determined by the relative positioning of the cams on the actuator.

2. In a device for forming complex bends in wires, a plurality of pairs of movable members, each pair of members having opposed forming surfaces, the pairs being linearly aligned, adjustable spring biasing means for each of the members for driving the members to converge on a wire positioned therebetween, an actuator normally holding the members apart, means for moving the actuator and individual cams for each of the members on the actuator for sequentially releasing the forming members.

3. In a device for forming complex bends in wires, a plurality of pairs of opposed forming members, adjustable spring biasing means for each of the members for driving the members to converge on a wire positioned therebetween, an actuator normally holding the members apart, means for moving the actuator, individual cams for each of the members on the actuator for releasing the forming members and adjustable means for limiting the travel of the forming members when released.

4. A device for progressively forming S bends in wires secured in and extending from a holder comprising a

base, a plurality of opposed forming members, means on the base for supporting the members for reciprocating motion, means on the base for supporting the holder to position wires extending therefrom between the members, adjustable spring biasing means for each of the members for driving the members to converge on the wires positioned therebetween, an actuator normally holding the members apart, means for moving the actuator, and individual cams for each of the members on the actuator for successively releasing the members to progressively form the wires.

5. A device for progressively forming S bends in wires secured in and extending from a holder comprising a base, a plurality of pairs of opposed forming members, a vertical support for the members on the base guides on the support for slidably mounting the members for reciprocating motion, spring biasing means on the support for driving opposing members of each pair of members to converge on each other, surfaces on the converging ends of each pair of members adapted to co-act to form a portion of the bend, an actuator normally holding the members apart, means on the base for moving the actuator, adjustable means for limiting the travel of the forming members when released and individual cams for each of the members on the actuator for successively releasing the members to progressively form the wires.

6. In a device for forming complex bends in strip material, a plurality of opposed, movable forming members,

30 individual springs for urging the members to converge on strip material positioned therebetween, an actuator block, means for reciprocating the block, and individual cams on the block for spreading each of the forming members apart for receiving strip material therebetween when the reciprocating means moves the block in one direction and 35 for releasing the members in a desired sequence to form the strip material when the reciprocating means moves the block in the opposite direction.

7. In a device for forming complex bends in strip material, a plurality of opposed, movable forming members,

40 individual driving means for each of the members for urging the members to converge and deform strip material therebetween, an actuator normally supported in a first position, means for moving the actuator from its first position to a second position, individual camming means on the actuator for each of the members for holding the members separated for receiving strip material therebetween when the actuator is in its first position, and 45 means for positioning the cams on the actuator to release the individual driving means in a desired sequence to produce a desired sequence of bends in strip material positioned between the members when the actuator is moved to its second position.
